H. F. JEROLAMAN,
MECHANISM FOR OPERATING BOX CAR DOORS.
APPLICATION FILED JAN. 24, 1919.

ATTORNEYS.

UNITED STATES PATENT OFFICE.

HENRY F. JEROLAMAN, OF CHICAGO, ILLINOIS.

MECHANISM FOR OPERATING BOX-CAR DOORS.

1,301,445.

Specification of Letters Patent.

Patented Apr. 22, 1919.

Application filed January 24, 1919. Serial No. 272,883.

To all whom it may concern:

Be it known that I, HENRY F. JEROLAMAN, a citizen of the United States, and a resident of the city of Chicago, in the county of Cook 5 and State of Illinois, have invented a certain new and useful Improvement in Mechanism for Operating Box-Car Doors; and I do hereby declare that the following description of my said invention, taken in connection 10 with the accompanying sheet of drawing, forms a full, clear, and exact specification, which will enable others skilled in the art to which it appertains to make and use the same.

15 My invention relates generally to improvements in mechanism for operating box-car doors; and it consists, essentially, in the novel and peculiar combination of parts and details of construction, as hereinafter first 20 fully set forth and described and then pointed out in the claims.

The object of this invention is the production of an efficient, and serviceable mechanical means for opening and closing the 25 doors of box cars, which, especially in the, at present, prevailing employment of freight cars having a very large capacity and consequently increased weight, are rather difficult to open and close, the result of which 30 may be noticed by the inspection of a freight car of the nature mentioned, which has been in use for some time and shows the result and damages to the car door by the employment of a crow-bar which is generally resorted to in cases where the door cannot be 35 readily opened and closed.

In order to overcome this drawback, I construct the mechanism for opening and closing the car-door in the preferred embodiment 40 of my invention, as illustrated in the drawings forming a part of this specification, and in which—

Figure 1 is a side elevation of a portion of a box-car body, showing the door in 45 closed condition, and illustrating the application of my invention in position for opening the door. Fig. 2 is a like view showing the door in opened condition, and the mechanical means in position for closing the door. Fig. 3 is a sectional elevation on the indirect line 3—3 of Fig. 1. Fig. 4 is a sectional detail, on an enlarged scale, of a portion of the operating lever and associated parts. Fig. 5 is a sectional plan of 50 the door and parts thereon connected with

the operating mechanism. Fig. 6 is an elevation of a fragment of the device; and Fig. 7 is a plan of a portion of the device illustrated in Fig. 6.

Like parts are designated by the same characters and symbols of reference in all the various figures.

A, in the drawings designates a portion of a box-car body of usual construction; and B, the slideable door employed for closing the door opening C in said car body. There are two of these doors on each car, and they are usually provided with hangers 12, having track wheels moving on tracks 13, whereby the doors are suspended, and the car sills 14 are provided with brackets 15, which retain the lower ends of the doors in proper position when closed. There are also secured to the car body stops 16, which limit the distance to which the car doors may be moved in opening, and battens or stops 17, adjacent the door openings C to limit the closing movement of the door. As thus far described the car body and its doors are, as already stated, of usual construction, and it is to this class of cars to which my invention is best adapted for use.

The car sides and the doors are alike in construction, and I shall, therefore, refer to them and the operating mechanism in the singular number.

To the facing 18 above the door of the car body there are strongly secured, two outwardly extending brackets 19, 19^a, which are in spaced apart relationship, and the eyes of which receive a, preferably round, rod 20. Upon this rod there is slidably and slightly oscillatably mounted a depending lever D, which reaches downwardly to nearly the lower end of the door to bring it within convenient reach of an operator. This lever is a flat bar of proper dimensions, the upper end of which is twisted at an angle of approximately 45 degrees, as best shown in Figs. 6 and 7; and is punctured to engage the rod 20, as will hereinafter more fully appear.

Upon the face of the door, preferably slightly above the middle of the door there is securely fastened a flat bar E, extending entirely across the door and having its ends bent at right angles as shown at 21, Fig. 5, to embrace the two vertical edges of the door. From this bar extend a multiplicity of T-shaped projections 22, 22^a, 22^b, which

projections may be formed integrally with the bar E, or secured thereto in any approved manner; and over this bar there is placed a second bar F, which latter bar performs the function of a guard to prevent the lever D from moving outwardly beyond a predetermined limit.

Attention is now directed to the T-shaped projections on the bar E, under the heads 10 of which the lever D will be placed when the door is to be moved; and let it be assumed that the door B is closed and is to be opened: in this case the upper end of the lever D will be in close proximity of the bracket 19^a, and 15 be behind the T-shaped projection 22^a on the bar E. By now pulling at the end of the lever D, (the bracket 19^a and rod 20 forming the fulcrum of the lever, and the projection 22^a the point of resistance) the 20 door can be readily moved; and it is desirable to do so by a step-by-step movement, *i. e.* after having moved the door a certain distance the lever D is disengaged from the T-headed projection 22^a, swung over the 25 next succeeding projection 22^b, and another bite taken, which operation is repeated until the door B has been moved the desired distance. By operating the lever D as described, it will always be in a nearly perpendicular position and the force exerted upon 30 the door be, therefore, in line with the movement of the door, so that but a slight effort on the part of the operator will suffice to open the same, and wedging of the door 35 entirely prevented.

Projecting from the door near the upper and left margins thereof there is secured to the door a stop 24, which stop performs the function of moving the upper end of the 40 lever D upon the rod 20 toward the right when the door is being opened; and at the opposing margin of the door there is a like stop 25, which when the door is being closed pushes the upper end of the lever D back to 45 starting position. The object of thus shifting the fulcrum of the lever from one to the other bracket is to bring the lever D in approximately vertical position when employed in opening or closing the door, as 50 hereinbefore described.

I have hereinbefore indicated that the upper end of the lever D is twisted to an angle of approximately 45 degrees. The object of thus twisting the lever is to cause it to pinch 55 the bar 20 when desired by a slight axial rotation of the lever. In this case the lever will be operative for moving the door even should its upper end be at some distance from either bracket because it will be then held by 60 frictional contact upon the rod 20. In this connection I desire to state that while I prefer the twisted construction of the lever D, to an angle of 45 degrees, good results can be secured by twisting the upper end of the 65 lever D to an angle of 90 degrees, but in this

case the lever cannot be made to pinch upon the rod 20 as readily as when the angularity is 45 degrees. And I may also here state that fairly good results can be secured by making the fulcrum of the lever D a fixed 70 one, which can be accomplished by shifting the brackets 19, 19^a, close enough together to receive the upper end of the lever D between them and making the rod 20 correspondingly shorter. In this case the two 75 brackets 19, 19^a, should be in line with the right vertical margin of the door when closed, and, which is the same, be in line with the left vertical marginal line of the door when open. This will require that the 80 lever D be placed at an angle when first acting upon the door, but after the first step-movement has been made, subsequent steps may be the same as hereinbefore set forth.

I have hereinbefore stated that the bar E 85 extends the entire width of the door B which leads to the assumption that this bar is a single piece. While I prefer to thus make the bar, it is obvious that it may also be made in several pieces; and that the process of casting this bar or the pieces constituting this bar, can be readily produced in the process of casting in malleable iron or mild cast steel.

While I have hereinbefore described the 95 preferred embodiment of my invention, I desire it to be understood that I am aware that changes in the details of construction may be made, and parts omitted without departing from the scope of my invention as 100 defined in the subjoined claims.

Having thus full described this invention, I claim as new, and desire to secure to me by Letters Patent of the United States the following claims—

1. Mechanism for opening and closing the doors of box cars, comprising, in combination, a car body, a slidable door, a fulcrum secured to the car body above said door in close proximity to the upper edge of the 110 door; a lever pivotally connected to said fulcrum, said lever being constructed to swing pendulum-fashion across the face of the door, a bar, said bar being longitudinally secured to the face of the door, said bar having a series of spaced-apart projections which said lever is constructed to engage to open and close said door by a step-by-step movement of said lever.

2. Mechanism for opening and closing the 120 doors of box cars, comprising, in combination, a car body, a slidable door, a fulcrum secured to said car body above said door, a lever pivotally connected to said fulcrum, a bar, said bar being longitudinally secured 125 to the face of the door above the middle of the door, said bar having a series of spaced-apart projections which said lever is constructed to engage to open and close the door by a step-by-step movement of said 130

lever, and a guard for said lever to prevent outward movement of said lever beyond a predetermined distance.

3. Mechanism for opening and closing the doors of box cars, comprising, in combination, a car body, a slidable door, a fulcrum secured to said car body above said door in close proximity to the upper edge of the door, a lever pivotally connected to said fulcrum, a bar, said bar being longitudinally secured to the face of the door, said bar having a series of spaced apart, T-shaped projections which said lever is constructed to engage to open and close said door by a step-by-step movement of said lever, said lever being constructed to swing pendulum-like across the face of the door and over said bar.

4. Mechanism for opening and closing the doors of box cars, comprising, in combination, a car body, a slidable door mounted on said car body, a fulcrum secured to said car body above said door, a lever pivotally connected to said fulcrum, a bar secured to the face of said door above the middle thereof, said bar having a series of spaced apart, T-shaped projections which said lever is constructed to engage to open and close the door by a step-by-step movement, and a guard over said bar to prevent outward movement of said lever beyond a predetermined distance.

5. Mechanism for opening and closing the doors of box cars, comprising, in combination, a car body, a slidable door mounted on said car body, a pair of spaced-apart brackets secured to said car body above said door, a rod connecting said brackets, a lever rotatably and slidably mounted on said rod, a bar secured to the face of the door above the middle of said door, said bar having a series of spaced-apart projections which said lever is constructed to engage to move said door by a step-by-step movement of said lever.

45 6. Mechanism for closing and opening the doors of box cars, comprising, in combination, a car body, a door slidably mounted on said car body, a pair of spaced-apart brackets secured to said car body above said door, a rod connecting said brackets, a lever rotatably and slidably mounted on said rod, a bar secured to the face of the door above the middle portion of said door, said bar having a series of spaced-apart projections which said lever is constructed to engage to move said door by a step-by-step movement

and a guard on said door for preventing outward movement of said lever beyond a predetermined distance.

7. Mechanism for opening and closing the doors of box cars, comprising, in combination, a car body, a door slidably mounted on said car body, a pair of spaced-apart brackets secured to said car body above said door, a rod connecting said brackets, a lever rotatably and slidably mounted on said rod, a bar secured to the face of the door above the middle portion thereof, said bar having a series of spaced-apart, T-shaped projections which said lever is constructed to engage to move said door by a step-by-step movement, and a guard on said door for preventing outward movement of said lever beyond a predetermined distance.

8. Mechanism for opening and closing the doors of box cars, comprising, in combination, a car body, a door slidably mounted on said car body, a pair of spaced apart brackets secured to said car body above said door, a rod connecting said brackets, a lever rotatably and slidably mounted on said rod, a bar secured to the face of the door above the middle portion thereof, said bar having a series of spaced-apart, T-shaped projections which said lever is constructed to engage to move the door by a step-by-step movement, and a guard on said bar and in spaced relation thereto to prevent said lever from moving outwardly beyond a predetermined distance.

9. Mechanism for operating the doors of box cars, comprising a car body, a door slidably mounted on said car body, a pair of spaced-apart brackets secured to said car body above said door, a rod connecting said brackets, a lever rotatably and slidably mounted on said rod, a bar secured to the face of the door above the middle portion of said door, said bar having a series of T-shaped projections which said lever is constructed to engage to move said door by a step-by-step movement, a guard on said bar in spaced relationship thereto to limit the outward movement of said lever beyond a predetermined distance, and stops on said door for moving the upper end of said lever upon said rod.

In testimony that I claim the foregoing as my invention, I have hereunto set my hand.

HENRY F. JEROLAMAN.
